CLARENCE LIPPER, OF PHILADELPHIA, PENNSYLVANIA, ASSIGNOR TO LIPPER MANUFACTURING CO., INC., OF PHILADELPHIA, PENNSYLVANIA, A CORPORATION OF PENNSYLVANIA.

TEXTILE FABRIC.

Application filed October 6, 1928. Serial No. 310,873.

REISSUED

My invention relates to a new and useful improvement in textile fabric and it relates more particularly to a novel woven fabric having a resilient stiffening mesh on one side thereof invisible from the face side and woven simultaneously with the body of the fabric and interlaced therewith at intervals just sufficiently frequent to afford the body fabric the necessary support when in use.

10 For the purpose of illustrating my invention I have shown in the accompanying drawings one form thereof which is at present preferred by me, since the same has been found in practice to give satisfactory and reliable 15 results, although it is to be understood that the various instrumentalities of which my invention consists can be variously arranged and organized and that my invention is not limited to the precise arrangement and organization of the instrumentalities as herein 20 shown and described.

Figure 1 represents a top plan view of a fabric embodying my invention, shown on a greatly enlarged scale and in a somewhat diagrammatic manner.

Figure 2 represents a plan view of the reverse or back side of the fabric similarly enlarged and also in a diagrammatic manner.

Figure 3 represents a section on line 3—3 30 of Figure 2 taken parallel to the warp of the fabric and with the warp threads of the body omitted from the drawing for greater clarity.

Figure 4 represents a section on line 4—4 35 of Figure 2 taken parallel to the weft of the fabric and with the body weft threads omitted for greater clarity.

The novel fabric of my present invention may be woven on a loom with two sets of warp threads and two sets of weft threads, 40 or two shuttles.

The warp threads of the body as well as the weft threads of the body may be any suitable material, while the warp and weft threads of the stiffening mesh or weave may 45 be any suitable stiffening strands as horsehair, artificial horsehair, or the like.

In the particular embodiment of my invention shown in the drawings, the fabric is especially adapted for use in making ladies' hats. Thus, for instance, in this particular embodiment I employ for the body warp and weft threads, suitable flat strands of visca or other artificial cellulose product, such as artificial straw or the like. By "artificial cellulose" I comprehend the various regenerated

cellulose products as well as cellulose derivatives.

The body weft and warp strands designated by the numerals 1 and 2 respectively, are each composed of two or more independent flat threads of visca or other suitable material and the general cross-section of the entire warp or weft strand is correspondingly flat.

In Figures 3 and 4 of the drawings I have, 65 for the sake of illustration, shown in cross-section the wefts and warps respectively, as formed of two flat threads *a* and *b*, although in actual practice more than two threads go to make up a body warp and a body weft 70 strand.

On the reverse side of the fabric, shown particularly in Figure 2, there are disposed two right angular sets of stiffening strands running weft-wise and warp-wise, and designated by the numerals 3 and 4 respectively. The stiffening threads 3 and 4 are less frequent than the body weft and warp threads 1 and 2 respectively and may be laid as frequently as desirable. In the particular embodiment of my invention illustrated in the drawings there are one half as many stiffening strands as there are body weft and warp strands. Thus the stiffening strands 3 and 4 are interwoven with each other in a plain 85 weave to form a relatively open mesh or gauze on the reverse side surface of the body of the fabric.

The weave of the body of the fabric formed of weft and warp strands 1 and 2 and the weave of the stiffening mesh formed of the strands 3 and 4 are independent of each other except for an occasional interlacing of the warp reinforcing threads 4 with the "*a*" threads of certain of the weft body strands 95

1. Thus in the particular embodiment of my invention, shown in the drawing, the warp reinforcing threads 3 and 4 interlace with the thread "*a*" of every fourth body weft strand 1, thereby to establish a connection between the body weave and the reinforcing or stiffening mesh or gauze on the rear surface of the body. The interlacing of adjacent warp stiffening threads 4 with the body weft strands 1 is preferably staggered, as indicated 100 particularly in Figure 2, so that two adjacent stiffening warp strands 4 will not interlace with the same body weft strands 1 but will interlace with every second or some intermediate body weft strand, depending 110

upon the frequency of interlacing between the stiffening warp strands and body weft strands. By this means, the attachment points between the body fabric and the reinforcing or stiffening mesh or weave is distributed more uniformly throughout the surface of the fabric.

In the drawings, the fabric has been much enlarged so as more clearly to illustrate the invention and thus the spaces between the body weft strands and body warp strands have been likewise enlarged. Thus, in Figure 1, the stiffening weft and warp strands 3 and 4 are visible through the open spaces between the body weft and warp strands 1 and 2. In the actual fabric, however, the space between the body weft strands and body warp strands is practically negligible so that the stiffening strands 3 and 4 are entirely invisible from the face surface of the fabric (Figure 1).

By my novel construction therefore I am able to produce a fabric of any suitable weave or texture and to so reinforce or stiffen the fabric on the reverse side thereof as not to be at all visible on the face thereof and so as also to minimize the weight or thickness of the resultant product. Thus, a fabric embodying my invention may be woven in any desired weave and a stiffening gauze or mesh may be applied to the rear surface without destroying or in any way affecting the surface texture.

My novel fabric finds numerous applications, particularly in fabric designed for use in hats and the like. Thus, my invention is particularly applicable to the making of visca or artificial cellulose fabrics for ladies' hats and the like, which the rear stiffening mesh or gauze attached to the rear face of the fabric will so stiffen the fabric as to afford the same support sufficient to maintain the shape of the hat without any wire or any other bracing, or sizing, or the like.

The stiffening mesh of my novel fabric may be formed of natural hair threads or artificial hair threads of artificial cellulose or the like such as artificial horse-hair, or in fact any suitable stiff thread.

Having thus described my invention what I claim as new and desire to secure by Letters Patent, is:—

1. A textile hat fabric of the character stated, comprising a body formed of artificial cellulose warp and weft threads interlaced in any suitable manner, and a stiffening mesh on one side of said body and invisible from the other side thereof, said stiffening mesh being formed of threads having suitable resiliency and being interlaced with body threads at intervals.

2. A textile fabric comprising a body formed of multi-strand artificial cellulose warp and weft threads interlaced with each other in any suitable manner, and a stiffening

mesh on one side of said body and invisible from the other side thereof composed of threads of suitable resiliency passed between constituent elements of the individual strands of the body threads at suitable intervals.

3. A textile hat fabric comprising a body formed of multi-strand warp and weft threads interlaced with each other and a stiffening mesh on one side of said body, composed of artificial cellulose threads of suitable resiliency interwoven between constituent elements of the individual strands of the multi-strand body threads at suitable intervals.

4. A textile fabric comprising a body formed of multi-strand artificial cellulose threads, interlaced with each other in any suitable manner and a stiffening mesh on one side of said body, composed of artificial cellulose threads of suitable stiffness passed between constituent elements of the multi-strand body threads at suitable intervals.

5. A textile fabric comprising a body formed of artificial cellulose threads interlaced with each other in any suitable manner and a stiffening mesh on one side of said body, formed of sets of artificial cellulose warp and weft threads of suitable stiffness, only one of said sets of stiffening threads being interlaced with threads of the body at intervals.

6. A textile fabric comprising a body formed of artificial straw warp and weft threads and a stiffening mesh on one side of said body, formed of artificial cellulose threads of suitable stiffness interlaced with body threads at intervals.

7. A textile fabric of the character stated comprising a body formed of artificial straw warp and weft threads interlaced in any suitable manner and a stiffening mesh on one side of said body, formed of sets of warp and weft threads of suitable stiffness; one of said sets of stiffening threads being interlaced with threads of the body at intervals.

8. A textile fabric including a body comprising relatively flat, ribbon-like, artificial cellulose threads and stiffening threads on one side of said body, interlaced with threads of said body at suitable intervals.

9. A textile fabric including a body comprising relatively flat, ribbon-like, artificial cellulose threads and relatively round artificial cellulose stiffening threads on one side of said body, interlaced with threads of said body at suitable intervals.

10. A textile fabric including a body comprising relatively flat, ribbon-like, artificial cellulose threads and a stiffening mesh on one side of said body, comprising relatively round artificial cellulose stiffening threads interlaced with said body threads at suitable intervals.

CLARENCE LIPPER.
